UNITED STATES PATENT OFFICE.

STEVEN DUICH, OF COLFAX, IOWA, ASSIGNOR OF ONE-HALF TO WILLIAM HUGHES,
OF COLFAX, IOWA.

WASHING-MACHINE GEARING.

1,251,993.

Specification of Letters Patent.

Patented Jan. 1, 1918.

Application filed August 30, 1916. Serial No. 117,637.

To all whom it may concern:

Be it known that I, STEVEN DUICH, a citizen of the United States, and a resident of Colfax, in the county of Jasper and the State of Iowa, have invented a certain new and useful Washing-Machine Gearing, of which the following is a specification.

The object of my invention is to provide a washing machine having a gearing which may be attached to the cover and be independent of the body of the tub.

A further object is to provide a washing machine gearing of extremely simple durable and inexpensive construction.

15 A further object is to provide such a gearing as will be light and easily operated by hand, yet positive and efficient.

20 A further object is to provide such a gearing that the effort required to operate it, may be readily varied to meet the requirements of the particular washing to be done, by varying the amount of revolution of the dolly in each direction.

25 My invention consists in the construction, arrangement, and combination of the various parts of the device whereby the objects contemplated are attained as hereinafter more fully set forth pointed out in my claims and illustrated in the accompanying drawings 30 in which:

Figure 1 shows a top plan view taken on the line 1-1 of Fig. 2, and, in which Fig. 2, shows a vertical sectional view taken on the line 2-2 of Fig. 1.

35 In the accompanying drawings I have used the reference numeral 10, to indicate generally a tub, such as is commonly used in connection with dolly washing machines. The tub 10, is supported by legs 11, a cover 40 is provided which consists of a small segment 12, fixed to the tub 10, and the large segment 14, which is hinged at 13, to the fixed segment.

45 The segment 14, is of such a size that its outside edges extend outwardly, slightly beyond the outside upper edge of the tub.

The segment 14, is reinforced by a supplemental layer of material 15, on its under side which is of such a size that its outside edges register with the inside upper edges of the tub, thereby forming a substantially annular shoulder extending from the cover proper into the tub to prevent lateral movement of the cover.

55 A suitable locking device 47, is provided to hold the segment 14, in its closed position.

Fixed to the upper side of the cover 14, near its center and on a line parallel to the axis of the hinge 13, is a strip of material 16, which extends substantially the width 60 of the cover. An upright 17, having a horizontal bearing at its upper end is fixed to the strip 16, near one end.

Journalized in the bearing 18, is a shaft 19, which has at the inside end a bevel pinion 65 22, and at the other end a balance wheel 20, which is operated by the handle 21. An upright 23, is fixed to the strip 16, and has a bevel pinion 24, journalized horizontally 70 thereon, which is adapted to mesh with the bevel pinion 22.

A wrist-pin 42, is fixed in the upper surface of the bevel pinion 24. A second strip 75 of material 25, is placed some distance above the strip 16, and parallel thereto, which has its ends extended down to the strip 16, to form supports. The outside end of the strip 25, is then bent inwardly to form a flange 27, which is fixed to the strip 16, by any suitable means as for instance, the bolt 28.

Bearings 29 and 30 are provided in vertical alinement in the strips 25, and 16 respectively and are in the center of the tub.

85 A vertical shaft 31 is mounted for rotation in these bearings and has at its lower end an ordinary dolly 32, and between the bearings 29, and 30, the small pinion 33. Near the bearings 29 and 30, a similar pair of bearings 34, and 35 are placed in which 90 bearings a vertical shaft 36, is rotatably mounted. Shaft 36 is provided between the bearings 34 and 35 with a larger pinion 37, adapted to mesh with the pinion 33 and has a horizontal disk 38 fixed to its upper end 95 slightly above the bearing 34. Arranged in the disk 38, at different distances from the axis of the shaft 36, are openings 39 which have raised bearing surfaces 40, surrounding them.

100 A crank-pin 41, is selectively and detachably secured in one of the openings 39. Pitman 43 is journalized at one end on the wrist-pin 42, and at its other end on the crank-pin 41. The respective distances between the axis of pinion 24 and crank-pin 42, and the axis of shaft 35, and each of the openings 39, are such that the operation

2

of the pitman 43 causes the disk 38, to rotate first in one direction and then the other, when the pinion 24, is continuously revolved.

Surrounding and covering the gearing is a removable case or cover 44, which is fastened to the cover by the screws 46. A vertical slot 45, is provided in the cover 44 adjacent to the balance wheel 20, to allow the passage of shaft 19. In the practical operation of my device, I fill the tub partly full of soapy water and dirty clothes and clamp down the cover 14. The balance wheel 20, is then rotated, which in turn imparts rotation to the bevel pinion 24, through the intermediate bevel pinion 22, and shaft 19. The rotation of the crank-pin 42, reciprocates the pitman 43 and imparts an alternating rotary movement to the disk 38, through the wrist-pin 41. The rotation of the disk 38 causes a similar movement of the large pinion 37, which in turn imparts a similar movement to the pinion 33 and the dolly 32.

The use of the large pinion 37, allows a greater range of rotation in each direction to the dolly than could be accompanied by connecting the pitman 43 direct to the pinion 33. The openings 39 and the disk 38 allow the operator to regulate the amount of rotation of the dolly in each direction and effect a change in the gearing ratio of the balance wheel 20 to the revolution of the dolly.

It will be understood that some changes 35
may be made in the construction and ar-
rangement of the parts of my improved
washing machine gearing without depart-
ing from its essential features and purposes,
and it is my intent to cover by this applica- 40
tion any changes which may be included
within the scope of my claims.

I claim as my invention:

In a device of the class described, a support, three spaced parallel shafts mounted thereon and arranged in the same vertical plane, a pinion mounted on the central shaft, a larger pinion and a disk mounted on one of the other shafts, the pinion being adapted to mesh with the first described pinion and the disk having a plurality of spaced openings therein, removed varying distances from the periphery of said disk, a detachable wrist pin selectively mounted in one of said openings, a pinion mounted on the third shaft, a crank pin fixed in said pinion, a pitman having one end pivoted to the crank pin and the other end pivoted to said wrist pin, and means for imparting rotation to the last described pinion, the parts being so arranged that rotation of the last described pinion imparts to the disk oscillating movement of varying degree according to which of the several openings the wrist pin is received in. 45 50 55 60

Des Moines, Iowa, August 10, 1916.

STEVEN DUICH.
